UNITED STATES PATENT OFFICE.

ADOLPHUS G. SNELL, OF NEW HAVEN, CONNECTICUT.

CANOPY FOR CHILDREN'S CARRIAGES.

SPECIFICATION forming part of Letters Patent No. 398,667, dated February 26, 1889.

Application filed December 14, 1888. Serial No. 293,612. (No model.)

To all whom it may concern:

Be it known that I, ADOLPHUS G. SNELL, of New Haven, in the county of New Haven and State of Connecticut, have invented a new 5 Improvement in Canopies for Children's Carriages; and I do hereby declare the following, when taken in connection with accompanying drawings and the letters of reference marked thereon, to be a full, clear, and exact 10 description of the same, and which said drawings constitute part of this specification, and represent, in—

Figure 1, a section of the canopy-frame, showing side view of the runner and notch in 15 half-vertical section, with the parts in the open position; Fig. 2, the stretcher and runner parts, each in vertical section detached; Fig. 3, a modification.

This invention relates to an improvement 20 in that class of canopies for children's carriages which are in the form of an umbrella—that is, one which is composed of a notch with ribs hinged thereto and a runner with stretchers hinged thereto and to the ribs, and in 25 which, when the umbrella is open, the runner rises to a point above the plane in which the stretchers are hinged to the ribs, and so that the reactive force of the cover upon the ribs through the stretchers tends to hold the runner in the up position, and in which no staff 30 is employed, the runner in opening being raised until it comes against a suitable stop near the notch, and so that by drawing the runner away from such stop the canopy or 35 umbrella may be closed. In this class of canopies the notch and runner have been constructed to set one against the other or with projection from one to enter a corresponding recess in the other; but in the first instance 40 there is a liability for the runner to be thrown out of place, and in the second instance there is difficulty in properly bringing the two parts together, so that they may be firmly seated the one upon the other.

45 The object of my invention is to overcome this difficulty and provide in the two parts, each made of metal, means for insuring the two parts coming together and so interlocking when together that lateral movement of 50 the runner with relation to the notch is impossible; and the invention consists in the

construction, as hereinafter described, and particularly recited in the claim.

A represents the notch, to which the ribs B are hinged in the usual manner. The notch 55 is hinged to a suitable clamping-piece, C, above, by which the canopy may be suspended—a common device in children's carriages and not necessary to be particularly described. Below the notch is a downward extension, D, which is of tubular shape, its lower end expanded to form a flaring mouth, E.

F represents the runner, which is of usual form, and to which the braces G are hinged in the usual manner, the said braces being also 65 hinged to the ribs in the usual manner, as at H. The runner is constructed with a stud, I, projecting from its upper end, made as an integral part thereof, the runner and the stretcher parts being made from cast metal. 70 This stud I corresponds to the interior of the tubular extension D from the notch, and is adapted to enter therein, as represented in half-section, Fig. 1. The runner is also provided with a handle, J, by which to facilitate 75 the opening and closing of the canopy.

The relation of the runner to the stretcher is such that when in the open or expanded position the runner will have taken the inner end of the stretchers to a plane above the 80 plane where the stretchers are hinged to the ribs, as in the usual construction.

By constructing the runner with the stud I, as I have described, and the notch with a tubular projection into which the stud I may 85 enter, it follows that when the parts are in the expanded position, as seen in Fig. 1, and the stud in place in the notch projection, no lateral movement of either the runner or stretcher can be made independent of the 90 other.

By making the mouth opening into the tubular extension D of the notch flaring or of funnel shape it serves as a guide to direct the stud on the runner to its place, so that in 95 opening, as the runner reaches a point near its full-open position, the stud will strike upon one side of the flaring mouth and be thereby guided directly into its place, thus avoiding any attention on the part of the person opening it, as the stud will necessarily 100 find its place or seat in the projection D, the

extent of the mouth being equal to the greatest possible variation in the lateral movement which either the runner or notch may receive independent of each other. This construction is extremely cheap, as the parts may be made from cast metal of the finished shape, so that no appreciable mechanical manipulation is necessary in the completion of the parts, and the two parts are substantially as firm with relation to each other as if a staff was employed upon which the runner could move or onto which it could pass as it approaches the notch.

While I prefer to make the stud on the runner and the seat with the flaring mouth as a part of the notch, this order may be reversed, as seen in Fig. 3, and still retain the same advantage of support for and funnel-shaped mouth to guide the stud into its seat.

It will be understood from the foregoing

that I do not claim, broadly, a carriage canopy or umbrella having the notch and runner made in separate parts and without staff, as such, I am aware, is not new; but

What I do claim is—

In a carriage-canopy substantially such as described, the combination of the notch A, to which the ribs are hinged, and the runner F, to which the stretchers are hinged, the one constructed with a tubular projection, D, as an integral part thereof and terminating in a flaring mouth opening into it, the other constructed with a stud, I, as an integral part thereof, corresponding to the interior of the tubular projection D, substantially as described.

ADOLPHUS G. SNELL.
